UNITED STATES PATENT OFFICE.

JOSEPH PINCKNEY CHAMBERS, OF CHATTANOOGA, TENNESSEE.

TIE-FASTENER.

No. 902,374.

Specification of Letters Patent.

Patented Oct. 27, 1908.

Application filed October 22, 1907. Serial No. 398,727.

To all whom it may concern:

Be it known that I, JOSEPH P. CHAMBERS, a citizen of the United States, and a resident of Chattanooga, in the county of Hamilton and State of Tennessee, have invented a new and Improved Tie-Fastener, of which the following is a full, clear, and exact description.

This invention relates to tie fasteners and 13 is particularly useful in fastening cord and the like about bales, bundles and packages.

An object of the invention is to provide a simple, strong and inexpensive tie fastener by means of which a flexible member such as 15 a cord can be firmly and rapidly secured about a package, and which permits the release of the cord without difficulty.

A further object of the invention is to provide a device of the class described, by means 20 of which a cord or the like which is passed in two directions about a package can be securely held in position, and which permits the cord to be released easily and rapidly.

The invention consists in the construction 25 and combination of parts to be more fully described hereinafter and particularly set forth in the claims.

Reference is to be had to the accompanying drawings forming a part of this specification, in which similar characters of reference indicate corresponding parts in all the views, and in which

Figure 1 is a perspective view showing a package with a cord passed thereabout and 35 held in position by means of my fastener; Fig. 2 is a plan view of the fastener; and Fig. 3 is a similar view of a modified form of the device.

Before proceeding to a more detailed explanation of my invention it should be understood that the same can be usefully employed in connection with objects of all kinds about which it is desired to pass a flexible member such as cord, twine and the like.

45 The fastener can be used in different sizes and in connection with corresponding binding means of different thicknesses and lengths. The device is so arranged that the line of the binding medium is secured at one end there-

50 to and is passed around upon all four sides of the object, the device presenting arms for holding the line suitably in position for the purpose, and having means for removably holding the opposite end of the line. The 55 construction is such that the line can be drawn as tightly as necessary and has its free

end securely held, notwithstanding that it is easily released by a proper manipulation when it is desired to untie the binding means.

Referring more particularly to Figs. 1 and 60 2 of the drawings, I prefer to fashion the tie from material such as wire of suitable stiffness; consequently this form of the invention has an elongated, bifurcated body which is fashioned from the wire by bending the latter upon itself to form the legs 1 and 2. Near the junction of the legs the latter are parallel and comprise a constricted neck 3 to which the end 4 of the line 5 can be easily fastened by knotting or in any other suitable 65 manner. The end of the leg 1 is laterally disposed and thereby is formed a concavity 6 for retaining the line 5 intermediate of the ends of the same, to permit the line to be passed in two directions about the object. 70 Beyond the concavity 6 the end of the leg 1 is formed into a laterally and upwardly disposed finger 7 for a purpose which will appear hereinafter.

The end of the leg 2 is bent upon itself to 75 form a tapered recess 8, which serves as a grip for the free end 9 of the line 5. At the same time the end of the leg 2 constitutes an arm 10 about which the line can be passed as will be shown hereinafter, the arm being 80 disposed for this purpose, away from the finger 7.

85 My invention is used as follows: The end 4 of the line is secured at the neck 3 of the bifurcated body. The device is held in position upon the package and the line is then passed around the same in one direction, being returned to the device and then being passed around the leg 1 at the concavity 6. In this way the direction of winding of the 90 line can be changed and the latter is passed about the object in a direction at right angles to the first winding. The end of the line 9 when it is returned to the device is passed around the finger 7 and the arm 10, the extremity being slipped into the tapered recess 8, which firmly grasps it and holds the line in 95 position and thus assists in forming a knot. It will be understood that with this device the line can be drawn as taut as desired, and 100 it can be easily released from the object by withdrawing the end from the recess 8.

105 In the modified form of my invention shown in Fig. 3, the tie fastener is cut, stamped or otherwise formed from suitable material such as sheet metal, and comprises a flat body 11, having at one side similar

curved and upwardly inclined arms 12, which correspond to the legs 1 and 2 of the bifurcated body shown in Fig. 2, and serve to hold the line intermediate of the ends and at the free end. The other end of the line is secured to the body 11 by means of an opening 13, formed therein, the line being inserted in the opening by means of a slot 13^a and provided with a knot at the opposite side to prevent its withdrawal through the opening. The slot 13^a connects the opening 13 and the inner edge of the body. Adjacent to one of the arms 12 of the body has at the edge a tapered recess 14, for gripping the free end of the line.

Having thus described my invention I claim as new, and desire to secure by Letters Patent:—

1. A tie fastener, comprising a body having means for holding a line at one end of the latter, a part formed to engage the line intermediate the ends of the same to permit the direction of the line to be changed, and a second part having a tapered recess, for gripping the line near the free end thereof, said first part adjacent to said second part having a finger, said finger being upwardly bent to permit the line to be looped thereabout before being inserted in said recess whereby a knot can be formed.
2. A tie fastener, comprising a body formed from a bent elongated member, and having means for permanently holding a line near one end of the latter, a portion curved to engage the line intermediate the ends of the same, a finger adjacent to said curved portion, and an arm separated from said finger and having a tapered recess, said

finger being upwardly bent to permit the line to be passed thereabout before being inserted in said tapered recess, whereby a knot can be formed, said arm being inclined away from said finger, said curved portion, said finger and said arm being substantially in alinement.

3. A tie fastener, comprising a body having means for permanently holding a line near one end of the latter, a portion presenting a concavity adapted to retain the line intermediate of the ends of the same, a laterally and upwardly disposed finger adjacent to said portion, and an arm adapted to have the line passed thereabout and presenting a tapered recess for gripping the line, said concavity, said finger, and said recess lying substantially in alinement transversely of the length of the fastener.

4. A tie fastener, comprising an elongated body bent upon itself and adapted to be secured at the bend, said body having at one side of the bend a portion presenting a concavity adapted to retain the line intermediate of the ends of the same and a laterally and upwardly disposed finger adjacent to said concavity, said body further having at the other side of the bend an arm adapted to have the line passed thereabout and presenting a tapered recess for gripping the line.

In testimony whereof I have signed my name to this specification in the presence of two subscribing witnesses.

JOSEPH PINCKNEY CHAMBERS.
